(57) **CLAIM**

The ornamental design for an edge plane, as shown and described.

DESCRIPTION

FIG. 1 is a front, top, right side isometric perspective of the edge plane of the present invention;

FIG. 2 is a front elevation of FIG. 1;

FIG. 3 is a rear elevation of FIG. 1;

FIG. 4 is a top plan view thereof;

FIG. 5 is a bottom plan view thereof;

FIG. 6 is a left side elevation view thereof; and,

FIG. 7 is a right side elevation view thereof.

The broken lines illustrate portions of the edge plane which form no part of the claimed design.
